DEVICE FOR NOTCHING AN EDGE OF A FLEXIBLE WEB

Paul Levine, New York, N. Y., assignor of one-third to Hillel Levine, Brooklyn, N. Y., and one-third to James Levine, Flushing, N. Y.

Application August 12, 1948, Serial No. 43,858

11 Claims. (Cl. 164—42)

1

This invention relates to devices for notching an edge of a flexible web or cloth at predetermined distances.

An object of this invention is to provide a device of the character described, including rollers to feed a flexible web, motor means for rotating the rollers, a scissors for notching an edge of the web, and means controlled by the motor for periodically moving the scissors towards an edge of the web to receive the edge between the jaws of the scissors and for operating the scissors to notch the web, at predetermined longitudinal lengths with respect to the web.

Yet another object of this invention is to provide a device of the character described, including manually controlled clutch means to permit stopping of rotation of the web feeding means while permitting the notching means to operate.

Still a further object of this invention is to provide a device of the character described, in which the distances between the notches may be varied.

Still a further object of this invention is to provide a strong, compact and durable machine of the character described, which shall be relatively inexpensive to manufacture, which shall be sure and positive in operation, and yet practical and efficient to a high degree in use.

Other objects of this invention will in part be obvious and in part hereinafter pointed out.

The invention accordingly consists in the features of construction, combinations of elements, arrangement of parts and method steps which will be exemplified in the construction herein-after described, and of which the scope of invention will be indicated in the following claims.

In the accompanying drawings in which is shown various illustrative embodiments of this invention:

Fig. 1 is a front elevational view of a machine embodying the invention;

Fig. 2 is a side elevational view thereof;

Fig. 3 is a top plan view of a portion of the machine;

Fig. 4 is a cross-sectional view taken on the line 4—4 of Fig. 3;

Fig. 5 is an end view of the disc which controls the scissors;

Fig. 6 is a cross-sectional view of the clutch; and

Fig. 7 is a perspective view of the scissors and its operating mechanism.

Referring now in detail to the drawings, 10 designates the machine embodying the invention. The same comprises a frame 11 having side stan-

2

chions 12 and a top member 13. Each side stanchion 12 comprises horizontal base portions 14, a pair of upwardly and inwardly inclined legs 15, and a horizontal transverse member 16. The legs 12 are interconnected by front and rear parallel members 17 at the level of member 16 and supporting a platform 18 disposed below the top 13 of the frame.

The top member 13 of the frame extends forwardly of the legs 12. Attached to the legs 12 are a pair of upstanding brackets 20 inclined upwardly and rearwardly. Mounted on the top frame member 13 is a flat table top member 22. Mounted on the forwardly projecting portions 13a of member 13 are a pair of aligned bearing blocks 23 in which is journaled a horizontal shaft 24. Fixed to shaft 24 is a horizontal friction drive roller 25 covered with any suitable abrasive material to provide the friction. Loosely mounted on the shaft 24 is a pulley 26.

Pulley 26 is provided with a pair of parallel horizontal pins 27. The pulley 26 is retained against longitudinal movement on shaft 24 by collars or any other suitable manner. Slidably mounted on shaft 24 and adjacent to pulley 26 is a clutch sleeve 28. Sleeve 28 is formed with an L-shaped slot 29. Fixed to the shaft 24 and projecting in the slot 29 is a pin 30. The slot 29 has a longitudinal portion 29a and a portion 29b at right angles thereto. At the end of the clutch sleeve 28 adjacent to pulley 26, are a pair of holes 31 adapted to receive the pins 27. It will now be understood that when the clutch 28 is slidably moved to the left, looking at Fig. 3, the pins 27 will engage within the holes 31 for rotating the shaft 24 when the pulley 26 is rotated. When the clutch 28 is moved to the right to disengage pins 27 from the holes 31, rotation of the pulley will not rotate the shaft 24 or the roller 25. The clutch sleeve 28 may be formed with externally knurled portion 32 so that it may be readily grasped by the hand of the operator and moved to a desired position. When the pin 30 is moved into the offset portion 29b of the slot 29, the clutch will be held in inoperative position.

It will be noted that the sleeve 28 is counterbored at one end as at 30a. Fixed to the shaft 24 is a collar 30b which fits into the counterbore 30a. Between the collar 30b and the end of counterbore 30a is a coil compression spring 30c which urges sleeve toward the pulley 26.

Mounted on the platform 18 is an electric motor 35. The shaft 36 of the motor is connected through reduction gearing in a gear box 37 to an output shaft 38. On shaft 38 are a pair

of pulleys 39 and 40 next to each other and fixed to rotate with the shaft 38. The pulleys 39 and 26 are interconnected by a belt 41. It will now be understood that when the motor is energized the pulley 26 will be rotated, and when the sleeve 28 is moved to the left, the roller 25 will also be rotated for feeding a web 43 of cloth or any other suitable flexible sheet material, as will appear hereinafter.

Mounted on said frame portions 13a is a horizontal shaft 44 carrying an idler friction roller 45 which is almost tangent but slightly spaced from the roller 25. The roller 45 is covered with abrasive material to provide the friction. Also mounted on the front end of frame member 13a is a web tensioning device 50. The tensioning device 50 comprises a horizontal shaft 51 on which is pivoted end levers 52 interconnected by a pair of parallel shafts 53 and 54 on opposite sides of the shaft 51.

On the frame portions 20 are a pair of aligned bearing blocks 55 in which is journaled a horizontal shaft 56 carrying a roller 57. The bottom of the roller 57 is substantially at the level of the top of the roller 25.

Mounted on the upper ends of the frame member 20 are bearing blocks 58 carrying a horizontal shaft 59 in which is mounted a roller 60. The rollers 25, 45; 57, 60 are in alignment, that is, they are disposed between a common pair of parallel vertical planes. The roller 60 is at a greater height than the roller 57. The roller 45 is at a level below the level of roller 25.

The web 43 moves in the direction of the arrows shown in Fig. 2. The web passes first over the bar or shaft 53, under the shaft 51, over the shaft 54, then under and around the roller 45, then under and around roller 25, then under roller 57, then over roller 60, and the web is fed downwardly from the roller 60.

On shaft 59 is a pulley 61. The pulley 61 is belted to the pulley 40 by a belt 62. On shaft 56 is a pulley 64, and on shaft 59 is a pulley 65. The pulleys 64, 65 are interconnected by a crossing belt 66, so that the roller 57 will be rotated in a direction opposite to the direction of rotation of roller 60. The rollers 25 and 60 are rotated in the same direction. It will now be understood that when the motor is energized and the clutch is moved by the operator to the left, the web 43 will be moved longitudinally by drive roller 25 and roller 45 in the direction of the arrow shown in Fig. 2.

Means is provided to notch the edge 43a of the web 43 at predetermined spaced distances. To this end, there is mounted on shaft 24, a gear 70. Gear 70 and pulley 26 are fixedly mounted by set screws 70a and 26b respectively on a common sleeve 26a, loose on the shaft 24. On the frame 13 is a bracket 71 supporting a bearing 72 in which is journaled a horizontal shaft 73 carrying pinions 74 meshing with the gear 70. On shaft 73 is a worm 75.

Mounted on the platform or table top 22 is a bearing member 76 in which is journaled a horizontal shaft 77 disposed at right angles to the shafts 24 and 73. On shaft 77 is a worm wheel 78 meshing with the worm 75. Also fixed to the shaft 77 is an annular disc 79. The disc 79 is annular but at one part thereof, is a lug or projection 79 having a curved outer surface 80. Fixed to the face of disc 79 and spaced from the axial shaft 77 is a pivot pin 81. Fixed to the table top 22 is a guide 83 inclined rearwardly from the right to the left side of the machine,

looking to the front of the machine. The guide 83 comprises a bottom wall 84 and parallel upwardly and inwardly side guides 85. The guides 85 are fixed to the plate 84 by screws 85a.

5 Mounted on the bottom wall 84 and between the guides 85 is a flat horizontal plate 86. Fixed to the plate 86 are a pair of upstanding parallel blocks 87. The blocks 87 are fixed to the plate 86 by screws 87a.

10 Interconnecting the pin 81 on disc 78 with a pin 90 on one of the blocks 87 is a link 91. Received between the blocks 87 is one end 92 of a fixed shearing member 93. The rear end portion 92 of the shearing member 93 is fixed to the blocks 87 by a pair of transverse pins 94 passing through suitable openings in the blocks 87 and riveted thereto. Extending upwardly from said portion 92 is an inclined shearing jaw member 95 having a lower shearing edge 96.

15 Pivoted to portion 95 of shearing member 93 is a second shearing member 97. The shearing members 97 and 93 are pivoted together by a pivot 98.

20 The shearing member 97 comprises a shearing portion or jaw 99 having an upper shearing edge 100 complementary to the shearing edge 96. Extending from the shearing jaw 99 is a long arm 101 overlying and resting in the curved projection 79 of the disc 78. Arm 101 is interconnected to a platform 22 by a coil tension spring 103. The coil 103 pulls down on arm 101 and tends to rotate shearing member 97 in clockwise direction about the pivot 98.

25 It will now be understood that when the disc 78 rotates, the link 91 will reciprocate the plate 86 and the blocks 87. Reciprocation of said plate 86 will cause reciprocation of the shears 93, 97 as a whole. Furthermore, as the shears 93, 97 move to the left, looking at Fig. 1, the projection 79 will lower from its uppermost position permitting spring 103 to rotate the shearing jaw 99 of shear member 97 upwardly for notching edge 43a of the web 43. Thus, as the shear moves to the left, the edge 43a of the web will be received between the shearing jaws 95, 97 and such jaws will then close, so that the shear edges 96, 100 will notch the cloth.

30 It will furthermore be noted that the shearing jaws 95, 99 are inclined in the same direction as the guide 83, so that, as the web is fed, the notch will be substantially at right angles to the edge 43a. It will be noted that the inclination of the shears is in the direction of the movement of the web.

35 The rollers 25 and 45 may be covered by a sheet of emery cloth or other friction material if desired, as indicated by the numerals 25a and 45a. The rollers 57 and 60 may be covered by a sheet of felt, as indicated by the numerals 57a and 60a. When the clutch 28 is moved away from the pulley 26 the web will stop feeding. The web 43 passes around the rods 53, 51 and 54 and around the rollers 25 and 45 which have abrasive coverings. The back rollers 57 and 60 are covered with felt and the abrasive on the rollers 25 and 45 which stop moving keep the web from feeding. At the same time the shearing mechanism continues to operate because pulley 26 is fixed to rotate with the gear 70. The purpose of having the shearing mechanism continue operating when the web stops is to permit the operator to stop the regular notching operation if a portion of the web is spoiled or bad. When the operator comes to a bad part of the cloth she will permit the cloth to feed substantially to the end of the bad part and

declutch the web feed means while continuing to permit the shearing mechanism to move to a point where the shears are about to make a notch. She will then start the web feeding operation so that the first notch is made just past the bad part, and then the regular intermittent notching operation continues.

In order to vary the distance between notches, the worm 15 and worm wheel 18a may be changed to achieve the desired relationship between the rotation of disc 78 and the longitudinal movement of the web.

It will thus be seen that there is provided a device in which the several objects of this invention are achieved, and which is well adapted to meet the conditions of practical use.

As various possible embodiments might be made of the above invention, and as various changes might be made in the embodiment above set forth or shown in the accompanying drawing, the embodiment is to be interpreted as illustrative and not in a limiting sense.

Having thus described my invention, I claim as new and desire to secure by Letters Patent of the United States:

1. A machine for notching an edge of a web of flexible sheet material at equally spaced distances, comprising rollers around which the web is engaged, means to rotate the rollers for feeding the web, a rotary disc, means controlled by the rotating means for rotating said disc, a fixed guide, a member mounted for reciprocation on said guide, a link interconnecting said member with said disc for reciprocating said member as said disc rotates, shears comprising a pair of interpivoted members provided with shearing jaws, means to fix one of said interpivoted members to said reciprocating member, whereby to reciprocate said shears as said disc rotates, the other of the interpivoted members of said shears having an extension, and means on said disc engaging said extension for rotating said other of said interpivoted members.

2. A machine for notching an edge of a web of flexible sheet material at equally spaced distances, comprising rollers around which the web is engaged, means to rotate the rollers for feeding the web, a rotary disc, means controlled by the rotating means for rotating said disc, a fixed guide, a member mounted for reciprocation on said guide, a link interconnecting said member with said disc for reciprocating said member as said disc rotates, shears comprising a pair of interpivoted members provided with shearing jaws, means to fix one of said interpivoted members to said reciprocating member, whereby to reciprocate said shears as said disc rotates, the other of the interpivoted members of said shears having an extension, and means on said disc engaging said extension for rotating said other of said interpivoted members, and spring means for retaining said extension in engagement with said engaging means on said disc.

3. A machine of the character described, comprising a friction roller adapted to receive a web, a shaft carrying said roller and rotatable with said roller, a pulley loosely mounted on said shaft, clutch means to connect said shaft and pulley, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said

third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension.

10 4. A machine of the character described, comprising a friction roller adapted to receive a web, a shaft carrying said roller and rotatable with said roller, a pulley loosely mounted on said shaft, clutch means to connect said shaft and pulley, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension, and spring means to retain said extension in engagement with said projection on said disc.

20 5. A machine of the character described, comprising a friction roller adapted to receive a web, a shaft carrying said roller and rotatable with said roller, a pulley loosely mounted on said shaft, clutch means to connect said shaft and pulley, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension, and spring means to retain said extension in engagement with said projection on said disc, a second roller parallel to the first roller and adapted to receive said web, and means connected to said motor for rotating a second roller in the same direction as the first roller.

30 6. A machine of the character described, comprising a friction roller adapted to receive a web, a shaft carrying said roller and rotatable with said roller, a pulley loosely mounted on said shaft, clutch means to connect said shaft and pulley, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of inter-

pivoted members having shearing jaws, means to fix one of said members to said reciprocating member, the other interpivoted member having an extension, and an eccentric projection on said disc engaging said extension, and spring means to retain said extension in engagement with said projection on said disc, said reciprocating member being inclined relative to the direction of movement of the web.

7. A machine of the character described, comprising a friction roller adapted to receive a web, a shaft carrying said roller and rotatable with said roller, a pulley loosely mounted on said shaft, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension.

8. A machine of the character described, comprising a friction roller adapted to receive a web, a shaft carrying said roller and rotatable with said roller, a pulley loosely mounted on said shaft, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension, and spring means to retain said extension in engagement with said projection on said disc.

9. A machine of the character described, comprising a friction roller adapted to receive a web, a shaft carrying said roller and rotatable with said roller, a pulley loosely mounted on said shaft, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension, and spring means to retain said extension in engagement with said projection on said disc, a second roller parallel to the first roller and adapted to receive said web, and means connected to said motor for rotating a second roller in the same direction as the first roller.

10. A machine of the character described, com-

prising a friction roller adapted to receive a web, a shaft carrying said roller and rotatable with said roller, a pulley loosely mounted on said shaft, a gear loose on said shaft and fixed to the pulley for reciprocation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension, and spring means to retain said extension in engagement with said projection on said disc, a second roller parallel to the first roller and adapted to receive said web, and means connected to said motor for rotating a second roller in the same direction as the first roller, a third roller engageable by said web and means to cause said third roller to rotate in a direction opposite to direction of rotation of the second roller.

11. A machine of the character described, comprising a friction roller adapted to receive a web, a shaft carrying said roller and rotatable with said roller, a pulley loosely mounted on said shaft, a gear loose on said shaft and fixed to the pulley for rotation therewith, a second shaft parallel to the first shaft, a pinion on the second shaft meshing with said gear, a worm on said second shaft, a third shaft at right angles to the second shaft, a worm wheel on the third shaft meshing with said worm, a disc on said third shaft, a member mounted for reciprocation, a link interconnecting said member with said disc for reciprocating said member as said disc rotates, shears comprising a pair of interpivoted members having shearing jaws, means to fix one of said members to said reciprocating member, the other interpivoted member having an extension, and an eccentric projection on said disc engaging said extension, and spring means to retain said extension in engagement with said projection on said disc, a second roller parallel to the first roller and adapted to receive said web, and means connected to said motor for rotating a second roller in the same direction as the first roller, a third roller engageable by said web and means to cause said third roller to rotate in a direction opposite to direction of rotation of the second roller.

PAUL LEVINE.
